JAY H. HALL, OF CLEVELAND HEIGHTS, OHIO, ASSIGNOR TO THE ELECTRIC CONTROLLER & MANUFACTURING COMPANY, OF CLEVELAND, OHIO, A CORPORATION OF OHIO

CONTROL SYSTEM FOR ELECTRIC MOTORS

Application filed January 28, 1926. Serial No. 84,290.

My invention relates broadly to electric control systems, and more particularly to the control of electric motors by dynamic braking.

5 It is one object of this invention to provide for a synchronous motor a dynamic braking system which is quickly responsive to emergency control in case of accident to an operative of machinery driven by the motor.

10 Other objects pertaining to portions of the system are set forth hereinafter.

Referring to the accompanying drawings, Fig. 1 is a diagrammatic view of the said system with the motor at rest. Fig. 2 is 15 an end view of the main switch 6 and adjacent parts, looking at Fig. 1 from the left. Figs. 3 and 4 show diagrammatically two modifications of the tripping devices for the main switch.

20 Referring first to Figs. 1 and 2, 1 designates the armature of a synchronous motor having the field winding 2 supplied with current from a D. C. source through the electromagnetic contactors 3 and 4 operated by current in the winding 5.

6 is a switch having the movable member 7 carrying contacts 8 and 9 which in the running position of the switch engage the fixed contacts 10 and 11 and thereby connect the 30 supply lines L' and L3 through the resistances 12 and 13 to two of the motor leads, the third supply line L2 being simultaneously connected to the third motor lead through the contacts 14 and 15, as hereinafter explained.

16 and 17 are electromagnetic acceleration contactors operated by current in the winding 18 to shunt the current from lines L' and L3 around the resistances 12 and 13, 40 the winding 18 being controlled by the lock-out switch 19.

When the switch 6 moves to running position the electrically connected contacts 20 and 21 on the member 7 engage the fixed 45 contacts 22 and 22', and when the switch 6 moves to braking position the contacts 8, 9 and 21 on the member 7 engage the fixed contacts 23, 23' and 24. When the switch 6 is in running and braking positions the contacts 25 and 26 are in contact, and the con-

tacts 14 and 15 remain closed during the braking connection of the motor.

The mechanism for operating the switch 6 is shown in Fig. 2, now to be described. The U-shaped frame 27 has at opposite sides of the space between its side members the fixed bars 28 and 29, the former supporting the contacts 10, 11, 22 and 22', and the latter the contacts 14, 23, 23', 24 and 25. The frame carries the pole pieces 30 energizable by the winding 31 for causing the armature 32 pivoted on the frame at 33 to move toward themselves. The armature carries the support 34 on which the contacts 15 and 26 are mounted.

The armature 32 carries the arm 35 pivoted thereto and carrying the member 7 at its upper end. The arm 35 and a fixed point beneath the bar 28 support the end pivots of two toggle links 36 flexed downwardly, the pivot connecting their adjacent ends carrying the rod 37 resting on the helical spring 38, the lower end of the spring being supported by the arm 39 projecting from the hub of the armature 32.

The frame 27 supports the tripping lever 40 having one end provided with a catch for interlocking with the horizontal hook 41 carried by the toggle mechanism. The other end of the lever 40 lies over the plunger armature 42 in the trip coil 43. The trip lever 40 holds the hook normally at such a position that, when the armature 32 is actuated the switch member 7 will move to running position and be held thereby the trip lever.

The operation as to Figs. 1 and 2 is as follows, the parts being initially as on these figures. Upon closing the starting push-button switch 44 current flows in parallel circuits including in one circuit the winding of the relay 45 and the upper auxiliary contacts of the contactor 4, and in the other the winding 31, the contacts of the stopping push-button switch 46 and the time relay 47. Current in the said windings causes the armature 32 to be actuated, the switch 6 to be moved to the running position, and the relay 45 to be closed somewhat later owing to the dash-pot 48. The line L' is connected to the armature through the contacts 8 and 10, the resistance 12 and the winding of the

switch 19; the line L2, through the contacts 14 and 15; and the line L3, through the contacts 9 and 11 and the resistance 13.

During the period between the energizing 5 of the coil of the relay 45 and the closing of the same and of the contactors 3 and 4, the armature 1 is supposed to have been started in the usual manner with the field winding temporarily shorted through a suitable resistance 59. The relay 45 is made to close so slowly owing to the dash-pot 48 or other device that it is not until after the motor, which initially runs at reduced speed owing to the resistances 12 and 13 being in the motor circuit, has accelerated to a predetermined speed and thereby permitted the lock-out switch 19 to close the circuit of the winding 18 and cause the contactors 16 and 17 to short-circuit the resistances 12 and 13, that the relay 45 10 will close its contacts and cause the contactors 3 and 4 to close and connect the field winding 2 to a source of D. C. current, the said short-circuit including the field winding having been previously opened as in the usual practice. The short circuit of the field winding during the starting of synchronous motors is made through the resistance 59 and the contactor 3 and the back contact 60.

Upon the closure of the contactors 16 and 17 the motor is connected to full voltage through the contacts 8—10, 9—11, and 14—15 and accelerates to approximately synchronous speed.

The closing of the relay 45 connects the winding 5 in a shunt around the winding of the relay, whereupon the contactors 3 and 4 close, connecting the field winding 2 to a source of direct current and in series with the field rheostat 49. When the contactor 4 closed it opened its upper auxiliary contacts, thereby opening the circuit of the winding of the relay 45, which now drops open. The contactor 4 also closed its lower auxiliary contacts, thereby connecting the winding 5 in a maintaining circuit for the contactors 3 and 4. In order to prevent the release of the relay 45 from opening the circuit of the winding 5, the switch 6 upon moving to its running position closed the contacts 25 and 26 which like the relay 45 connects the winding to the line L2.

To stop the motor the push-button switch 46 is opened, thereby opening the circuit of the winding 31, whereupon the switch 6 opens and moves under the pressure of the spring 38 to the intermediate position shown in the drawings, and the contactors 3 and 4 open owing to the separation of the contacts 25 and 26. The contactors 16 and 17 also drop open because the circuit of the winding 18 is broken by the contact 21 leaving the contact 22'. The lock-out switch 19 was already open, as its winding was short-circuited by the contactor 16, the winding 18 being

kept in circuit by the auxiliary contacts 50 of the contactor 16, which were closed when this contactor closed.

51 is an emergency switch located conveniently for operation in case of an emergency requiring the stopping of the motor. This switch turns on the pivot 52 and is operated by the handles 53 and connects the winding of the relay 54 across the lines L2 and L3. If, when the motor is running, the switch 51 is opened, the relay 54 closes a circuit through the trip coil 43 and the contacts 20 and 22, whereupon the plunger armature 42 is caused to rise and disengage the trip lever 40 from the hook 41, permitting the spring 38 to straighten out the toggle links 36 and force the switch 6 to its braking position, in which the contacts 8, 21 and 9 engage the contacts 23, 24 and 23', respectively. The contacts 14 and 25 remain closed on the contacts 15 and 26, respectively, because the armature 32 which carries the contacts 15 and 26 remains closed.

The armature windings are now connected in closed dynamic braking circuits with the resistance 24'. As the field winding 2 remains energized, the motor is brought quickly to rest.

When the switch 6 is in braking position, the winding of the time relay 47 is in a closed circuit through the contacts 21 and 24, whereupon the relay after a slight delay owing to the dash-pot 55, opens its contact and thereby the circuit of the winding 31. The switch 6 then moves to its open or intermediate position, the contactors 3 and 4 open, and the relay 47 drops to its normal position. The contactors 16 and 17 opened when the switch went to braking position as they do when it goes to open position.

The relay 54 is moved to open position as soon as the switch 51 is closed by the springs 58. As long as the relay is closed the motor cannot start because the actuation of the armature 32 upon closing the switch 44 merely causes the braking position of the switch 6 to be reassumed, since the coil 43 will be energized and cause the tripping lever 40 to be tilted out of interlocking position with the hook 41. This ensures that the motor can not be started as long as the emergency switch is released which presumably will not occur until the emergency has passed.

In Fig. 1 a resistance 59 is connected in a closed circuit with the field winding 2 through the back contact 60 of the contactor 3, so that, when the contactors 3 and 4 open the field circuit, the field winding will be connected in the said closed circuit to furnish a field discharge circuit.

In Fig. 3 the relay 54 is omitted and the winding 43 is connected directly between the line L2 and one of the fixed contacts of the emergency switch. A spring 56 is provided to lift the outer end of the trip lever 40 and

pull it out of interlocking position with the hook 41 whenever current is cut off from the winding 43 by the opening of the emergency switch 51.

5 In Fig. 4 the parts are the same as in Fig. 3, except that the up-pulling spring 56 in the latter is replaced by an up-pushing spring 57 in the former, the lower end of the winding being connected directly to the line L2.

10 This application shows, but does not claim the subject matter claimed in applicant's application Serial No. 317,082, filed November 3, 1928.

I claim:

15 1. In a controller for synchronous motors, a source of alternating current supply, a source of direct current supply, a braking circuit, electro-responsive means for effecting the connection of the motor armature to the source of alternating current supply and for subsequently effecting the connection of the motor field to the source of direct current supply when the motor has accelerated to approximately synchronous speed, means 20 operated by the said electro-responsive means for setting up a bias for disconnecting the armature from the alternating current source of supply and connecting it to the braking circuit, a safety switch, and means depending upon current flowing in the safety switch for preventing the bias from becoming effective for the purposes described.

25 2. In a controller for synchronous motors, separate sources of current supply, a braking circuit, electro-responsive means for effecting the connection of the motor armature and field windings to the respective separate sources of supply, means made effective 30 by the said electro-responsive means for disconnecting the armature from its source of supply and connecting it to the braking circuit, a normally closed safety circuit, and means whereby a failure of current in the 35 safety circuit causes the electro-responsive means to become effective for disconnecting the armature from its source of supply and connecting it to the braking circuit.

3. In a motor control system, a motor, a 40 source of current supply, a stopping circuit, a set of contacts, an electromagnetic device for moving said contacts for connecting the armature of the motor to the said source, biasing means effected by the said electromagnetic device for moving said contacts to disconnect the armature from its source of supply and connect the armature to the stopping circuit, a safety circuit, holding means for said biasing means made effective by the 45 safety circuit, and means whereby a failure of current in the safety circuit causes the electro-magnetic device to disconnect the armature from the source and connect it to the stopping circuit.

4. In a control system, a source of alter-

nating current supply, a source of direct current supply, a synchronous motor, an electrical load element, an electro-magnetic device for effecting the closure of three sets of contacts, one set closed by the said device and 70 connecting the motor armature to the source of alternating current supply for running the motor, a second set closed by the device and thereby connecting the motor armature to the electrical load element and thereby 75 braking the motor, and a third set of contacts closed by the device in both the running and braking positions and thereby effecting the connection of the motor field to the source of direct current supply subsequently to the 80 closure of the first set of contacts.

5. In a motor system, a synchronous motor, a source of alternating current supply, a source of direct current supply, an electro-magnetic device for connecting the motor armature to the source of alternating current supply and for subsequently connecting the motor field to the source of direct current supply, an operating control circuit, a master switch connected to the control circuit for operating the electro-magnetic device, an electrical load element, and means for disconnecting the motor armature from the alternating current source and connecting it to the electrical load element, in combination 90 with a safety circuit, a normally closed switch therein, and means associated with the safety circuit and requiring the switch to be closed before the said device can be operated by the operating control circuit to connect the motor armature to the source of alternating current supply. 95

6. In a controller for synchronous motors, a source of alternating current supply, a source of direct current supply, a braking circuit, electro-responsive means for effecting the connection of the motor armature to the source of alternating current supply and the motor field to the source of direct current supply, means operated by the said device for setting up a bias for disconnecting the armature from the alternating current source of supply and connecting it to the braking circuit, and means for causing the said bias to become effective and disconnect the armature from the alternating current source of supply without disconnecting the motor field from the direct current source of supply, in combination with a normally closed safety circuit and means whereby a reduction of current in the safety circuit below a predetermined value causes the electro-magnetic device to operate the controller from the running position to the stopping position. 115

7. In a motor control system, an electric motor, a normally-open running circuit for the motor, a normally-open stopping circuit for the motor, a normally open circuit, means controlling the latter circuit and controlled thereby to effect the connection and discon-

- nection of the motor with respect to the said running and stopping circuits, a normally-closed safety circuit, and means whereby a reduction of current in the said safety circuit below a given value causes the motor to be disconnected from the running circuit and connected to the stopping circuit, and means for opening the stopping circuit when the motor has come to rest.
8. In a control system, an electric motor, a stopping circuit for the motor, a controller having a running position for connecting the motor to a source of supply, a stopping position for connecting the motor to the stopping circuit, and an off position having both circuits open, an electro-magnetic device for operating the controller, a normally-closed emergency circuit, and means whereby a failure of current in the said emergency circuit causes the said electro-magnetic device to operate the controller to disconnect the motor from the source of supply and connect the motor to the said stopping circuit.
9. In a control system for synchronous motors, an alternating current power circuit for the motor armature, a direct current power circuit for the motor field, a stopping circuit, a double-throw contactor with normally-open contacts, a winding for operating said contactor to connect the motor armature to the alternating current power circuit and for effecting a delayed connection of the motor field to the direct current power circuit, means for operating the double-throw contactor to disconnect the motor armature from the alternating current power circuit and connect it to the said stopping circuit, a normally-closed safety circuit, and means whereby upon the failure of current in the said safety circuit the motor armature is disconnected from the alternating current power circuit and connected to the stopping circuit while the field winding is still connected to the direct current power circuit.
10. For the control of a synchronous motor, alternating current and direct current power circuits, a stopping circuit, a set of normally open power contacts for connecting the motor armature to the alternating current power circuit and the motor field to the direct current power circuit, a set of normally-open stopping contacts for connecting the motor to the stopping circuit, an electromagnetic device for closing the alternating current power circuit and for effecting a delayed closure of the direct current field circuit, a pressure actuating mechanism operated by the electro-magnet which when pressure is released disconnects the motor armature from the alternating current power circuit and connects it to the stopping circuit, a normally-closed emergency circuit, and means whereby a reduction of current below a given value in the emergency circuits effects the release of the said mechanism to

open the alternating current power circuit and close the stopping circuit while the motor field is still connected to the direct current power circuit, and means for automatically disconnecting the field from the direct current power circuit when the motor has come to rest.

11. In a control system, a source of electric current supply, an electric motor, a running and a stopping circuit for the motor, a controller having a running position for connecting the motor to the source of supply, a stopping position for connecting the motor to the stopping circuit, and an off position for opening the running and stopping circuits and an operating control circuit and instrumentalities controlled by the latter circuit for closing two sets of contacts which are open at the off position, one of the said sets of contacts to close the running circuit of the motor in the running position only and the second set of contacts to close the stopping circuit of the motor in the stopping position only, in combination with a normally-closed safety circuit and means controlled by current in the safety circuit for preventing the closure of the second set of contacts by the instrumentalities controlled by the said operating control circuit.

In testimony whereof, I hereunto affix my signature.
